UNITED STATES PATENT OFFICE.

WILLARD C. JAMES, OF CUCAMONGA, CALIFORNIA.

COMBINED HEATER AND FOLDING FURNITURE.

No. 813,883.

Specification of Letters Patent.

Patented Feb 20, 1906.

Original application filed June 17, 1901, Serial No. 64,947. Divided and this application filed February 14, 1903, Serial No. 143,452.

To all whom it may concern:

Be it known that I, WILLARD C. JAMES, a citizen of the United States, residing at Cucamonga, in the county of San Bernardino and 5 State of California, have invented new and useful Improvements in a Combined Heater and Folding Furniture, of which the following is a specification.

The object of this invention is to economize space in living and sleeping rooms. This 10 I accomplish by forming a folding bed or similar article of furniture with heating means, such as a fireplace, that is exposed and brought into position for use when the bed is 15 folded up.

The invention is particularly intended for use in connection with a folding bed, such as shown in my Patent No. 700,501, dated May 20, 1902, granted on application, Serial No. 20 64,947, filed June 17, 1901, of which the present application is in part a division, such folding bed being pivoted in and acting as a closure for a recess in the wall of a room, so that when the bed is turned up the fireplace 25 assumes its natural position in the wall of the room. In said patent an imitation or representation of a fireplace was made in the bed-bottom; and the main object of my present invention is to provide for an actual operative fireplace in this connection, although it 30 may be applied with any kind of heating device and any article of folding wall furniture that may be suitable.

My invention further relates to improved 35 means for ventilation, to structural features whereby the combined article of furniture is rendered more stable when in raised position, more convenient and safe in operation, and more attractive in appearance, and to means 40 for safeguarding against escape of gas when the bed is in use.

The accompanying drawings illustrate the invention.

Figure I is a front view showing the bed in 45 folded-up or closed position in the wall of the room. Fig. II is a vertical section on the line II II of Fig. I, showing the bed in lowered position in full lines and in folded position in dotted lines. Fig. III is a detail section 50 of an automatic cut-off valve for the fuel-supply to the burner. Fig. IV is an edge view of part of the bed-frame and casing.

1 indicates a portion of the wall or casing of a room or chamber and 2 a portion of the

floor thereof. A recess 3 is provided in the 55 wall 1, and the bed-frame 4 is pivotally supported in said recess, preferably by trunnions 5 6 in the wall 1, in such manner as to enable the bed-frame to close the opening of the recess when said frame is folded or turned 60 up. The wall 1 therefore serves as a fixed support for the folding bed-frame, and the latter serves as a closure for the opening in the wall. The bottom of the bed-frame is formed with a fireplace 7, which is exposed in 65 front when the bed-frame is turned up, and a gas-supply conduit 10 is led to a burner 8 in said fireplace. A flue or conduit 11 for waste products of combustion is preferably provided leading from the fireplace, both of said 70 conduits preferably passing through the trunnions 5 6. The bed-frame 4 is suitably counterweighted by a weight 9. On the bottom of the bedstead or frame 4 is a shelf or 75 projecting flange 12 that serves as a foot or support for the bed when the frame is turned down and as a shelf or mantel when the bed is turned up.

The burner or heater 8 is rigidly secured to the bed-frame in such position that when the 80 bed-frame is in raised position this heater will be in front of and below the pivotal point, this being necessary to bring it to the usual position of a fireplace. As a consequence when the bed-frame is swung to low- 85 ered position the fireplace and heater will pass back into the casing or rear compartment, where it will be comparatively inaccessible. It is thus not practicable to use a flexible connection to this heater, as such connections are unavoidably subject to deterioration 90 and leakage, and must be kept in plain sight; but by leading the connection through the pivotal support I provide for a connection which may be made permanent and gas- 95 tight, a point of considerable importance in view of the serious results of leakage to the occupant of the bed. In the case of the outlet for the products of combustion this construction is especially necessary, as no flexible 100 connection of sufficient size or of the requisite heat-resisting capacity would be possible.

On the wall 1 above the opening of recess 3 is secured a shelf, ledge, or projection 13, and the bed-frame is preferably provided with posts, brackets, or projections 14, that when the bed is turned up engage and closely fit under the shelf or projection 13, so that

said posts or brackets serve to assist in the support of shelf 13, and the latter serves to frictionally hold the bed-frame in closed position. A spring catch or bolt 15 on one of 5 the posts or brackets 14, engaging in the fixed shelf 13, serves to insure retention of the bed-frame in folded position until said bolt is withdrawn. The shelf 13 and posts 14 serve as ornamental features of the mantel in conjunction with the mantelpiece 12, and the shelf 13 may also serve to temporarily receive articles from the mantel when the bed-frame is to be turned down. Above the shelf or mantelpiece 12 a mirror 16 is provided, the 10 shelf 13 serving as an entablature for the mirror and for the mantel as a whole. The shelf 13 projects from the casing-board 17, that extends over the open of recess 3, and cleats 18 are preferably secured on the back 15 of said casing-board to stiffen it, and by means of screws 19 passing through cleats 18, board 17, and into shelf 13 said cleats serve to assist in supporting the shelf 13.

Posts or side pieces 20 are secured on the 20 front of frame 4, the lower ends of these posts being beveled or inclined to permit them to swing back and clear the floor 1 when the bed-frame is turned down. A fixed casing 21 is arranged to surround the lower ends of 25 said posts 20 to conceal the open joint and at the same time give the effect of a pedestal.

The side extensions 22 22 of the pivoted frame 4 overlap the side posts or casing of the recess 3, so as to conceal the joint as far 30 as possible. Below the pivoted point, however, these extensions are cut away to allow the frame 4 to move back, and beads or strings 24 (see Fig. IV) are secured on the lower part of the casing at each side to take 35 the place, as far as regards the appearance or finish, of such cut-away portions, so that when the frame is raised the side line thereof is apparently continued without break.

The portion of the bed-frame front or bottom that is between the mantelpiece 12 and the floor is preferably boxed or advanced forward by a fireplace front or facing 25, finished with tiles or in other suitable manner, and the fireplace 7 is formed as a recess in 40 this front piece.

The recess 3 is desirably closed at the top except for a ventilating-opening 26, that may be closed by a hinged flap or valve 27, opening upward and controlled by a cord 28 passing 45 over a pulley 29 and extending downward through a notch 30 in the said flap, so as to be within reach of the person using the bed. This cord hangs to one side of the bed, so as not to interfere with raising the bed, and it is 50 provided on the end with a ring 31, which may be caught on a hook or nail 32 to hold the flap or ventilator 27 in open position. By this ventilator the bedclothing may be effectively ventilated when the bed is turned up 55 during the day.

A folding end board 40, constituting a headboard or footboard, may be hinged to the inner end of the bed, and when the bed is turned up this end board engages with the back wall of the bed-compartment and is thereby folded, so as to aid in holding the bedclothes in position.

Fluid fuel, such as gas, is supplied from the service-pipe 33 through a swivel-coupling 34 by the pipe or conduit 10, that passes through the hollow trunnion 5 and leads back of the front piece 25 to the gas-log, burner, or heater 8. A regulating-valve 35 in this pipe has a handle 36 extending forward of the front piece, so as to be accessible to the occupant 80 of the room when the fireplace is in operative position. When the fireplace is turned down, however, this valve is out of the way and cannot be meddled with by children or others who might otherwise turn on the gas when 85 the bed is down. To further insure against passage of gas under such conditions, I may provide a positive shut-off valve controlled by the movement of the bed-frame when the latter is turned down to shut off the gas-supply. Thus, as shown, the swivel-coupling 34 is formed with a port 39, that when the bed-frame is vertical allows free passage of gas and when said frame is turned down cuts off the gas connection. The trunnion 6 on the 90 other side of the bed-frame is also, preferably, made hollow and of sufficient size to receive a flue or conduit 11, that leads from the upper part of the fireplace 7 and turns freely in said trunnion, a sleeve or packing of asbestos 37 being desirably interposed. From the outer end of this hollow trunnion 6 a flue or chimney 38 leads upwardly to discharge the waste gases.

While my invention as above described is particularly applicable in connection with a folding bed, it may be applicable with other folding furniture, the bed and fireplace combination being selected as most appropriate, however, as it is not generally desired to use the fireplace during the time that the bed is occupied; nor is my invention limited to any particular form of heating device, as any suitable heater may be used.

What I claim, and desire to secure by Letters Patent of the United States, is—

1. A combined folding bed and heater comprising a fixed support, an inlet and an outlet pipe therein, a perforated bed-frame pivotally mounted in the support, a heater rigidly secured in the front of the frame, means at the rear of the frame for connecting the inlet with the heater, and means for connecting the perforation with the outlet.

2. A combined folding bed and heater comprising a support, an inlet and an outlet therein, a perforated bed-frame pivotally mounted in the support, a heater rigidly secured in the forward side of said frame, a pipe at the rear of the frame from the inlet to the

- heater provided with a valve, a handle from the valve to the front of the frame, and a conduit from the perforation to the outlet.
3. A combined folding bed and heater, comprising fixed supporting means, a bed-frame, pivotally supported in such means, and a heater, rigidly secured to the bed-frame, said bed-frame being provided with a recess serving as a fireplace for the heater, and a fuel-supply conduit leading through the pivotal support of the bed-frame and communicating with the heater.
4. A combined folding bed and heater, comprising fixed supporting means, a bed-frame, trunnions whereby said bed-frame is pivotally supported in the fixed supporting means, one of said trunnions being provided with a conduit therethrough for fuel, and the other trunnion being provided with a conduit therethrough for waste gases, and a burner and fireplace on the bed-frame respectively connected to said conduits.
5. A combined folding bed and heater, comprising fixed supporting means, a bed-frame on the fixed supporting means, trunnions whereby said bed-frame is pivotally supported in the fixed supporting means, one of said trunnions being provided with a fuel-supply passage, and the other with a passage for waste products of combustion, a burner on the bed-frame connected to said passages, and fuel-supply and waste flue pipes in the fixed supporting means connected to the respective passages.
- 35 6. A combined folding bed and heater comprising a support, a bed-frame therein, hollow trunnions between the frame and the sup-
- port, a heater in the forward side of the frame, a pipe from the heater to and projecting through one of the trunnions, the outer end 40 of which is perforated, an inlet pivotally mounted on said end of the pipe and adapted to communicate with said perforation when the bed-frame is in its vertical or folded position, and a ventilator communicating with 45 the heater and passing through the other trunnion.
7. A combined folding bed and heater comprising a fixed support, an inlet and an outlet pipe therein, a perforated bed-frame pivotally mounted in the support, a heater rigidly secured in the frame, means for connecting the inlet with the heater, and means for connecting the perforation with the outlet.
8. In an apartment construction, a bed- 55 holding compartment, and a bed-frame pivotally supported at the front of the compartment, a heater rigidly secured to said bed, in front of and below the pivotal support thereof so as to swing back into the compartment 60 as the bed-frame is lowered, and a fuel-supply conduit extending through the pivotal support of the bed and communicating with the heater.
- In testimony whereof I have signed my 65 name to this specification, in the presence of two subscribing witnesses, at Los Angeles, in the county of Los Angeles and State of California, this 7th day of February, 1903.
